FURNITURE CONSTRUCTION

William S. Holabird, Hamilton, Ind.

Application January 11, 1946, Serial No. 640,408

4 Claims. (Cl. 311—113)

1

This invention relates to furniture construction for tables and like structures having supporting legs, and particularly it relates to the attachment or mounting of the legs on such structures.

Where tables and like structures are to be provided with legs that are to be attached to the table top or the like after completion of the assembly of the top member, it has heretofore been found that such attachment has involved operational difficulties that resulted in delay in production as well as in increased cost of the product, and it is therefore an important object of the present invention to enable legs for tables and like structures to be secured in place in a simple and expeditious manner. A further and more specific object of the invention is to enable the depending side and end rails of a table or the like to be joined together by a metallic member that is not only decorative and ornamental in appearance but which also secures the legs in the desired relation to the top or other member that is to be supported by such legs.

Other and further objects related to the foregoing are to afford a novel and highly advantageous corner bracket for tables and the like; to enable such a corner bracket to be made from sheet metal; to afford a simple and effective interlocking connection between such a bracket and the elements of a table or the like in which the bracket is to be used; to enable the legs of a table or the like to be clamped and secured in position by such a bracket, and to enable such a bracket to be put in place subsequent to the assembly of the other elements of the structure.

Other and further objects of the present invention will be apparent from the following description and claims and are illustrated in the accompanying drawings which, by way of illustration shows a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a perspective view of a table embodying the features of the invention;

Fig. 2 is an enlarged fragmental cross sectional view taken substantially along the line 2—2 of Fig. 1 and showing the manner in which each leg of the table is associated with the table top;

Fig. 3 is a perspective view of the corner

2

bracket utilized in securing the legs in position; Fig. 4 is a fragmental sectional view taken along the line 4—4 of Fig. 1; and

Fig. 5 is a view similar to Fig. 2 and showing an alternative form of the invention.

In the form chosen for disclosure herein the invention is embodied in a rectangular table 10 having similar supporting legs 12 of the hairpin type secured at the respective corners of the table. The table 10 is in the present case illustrated as being of the extensible type having table top sections 14 that are separable along a central division line 16 and are associated for relative separating movement by means (not shown) of a conventional character. The table top sections 14 have depending side rails 18 and end rails 20 secured thereto in a conventional manner adjacent and parallel to the side and end edges thereof, as for example, in the manner shown in Fig. 4. As there shown, a connecting strip or block 22 is disposed in the inside corner so as to abut the lower surface of the top section 14 and the inside surface of the rail, as 18, and screws 24 and 26 are extended through the block 22 in a right angular relation so as to secure the block 22 to both the top 14 and the rail 18.

In accordance with the present invention the legs 12 are associated with the table top by means of corner brackets 30 which are so formed as to receive and clamp the upper ends of the legs 12 and also to form an artistic and rugged connection between the adjacent ends of the side and end rails 18 and 20. Thus, as shown in detail in Figs. 2 and 3, each bracket 30 is made from sheet metal so as to afford a connecting portion 31, and end clamps 32, disposed at opposite ends of the connecting portion 31. The end clamps 32 are parallel to each other and are adapted to receive and embrace the upper ends of the leg 12 that is to be associated therewith. In the present instance each leg 12 is formed from tubular metal stock, preferably chromium plated or otherwise finished to afford an attractive appearance, and this tubular stock is bent midway between its ends as at 12X to afford parallel portions 12R and 12L that are of equal length.

The end clamps 32 of the corner bracket 30 are arranged to embrace the upper ends of the tubular leg portions 12R and 12L with a substantial area of surface contact, and each end clamp 32 is formed to afford a bearing face 33 that is arranged to bear against the adjacent end of one of the side or end rails 18 or 20. Thus the bearing faces 33 are disposed at right angles to each other, as will be evident in Fig. 2, and the side

and end rails 18 and 20 are arranged to terminate in end faces 35 that are so spaced that when the clamping faces 33 of the bracket 30 are disposed against the end faces 35, the leg portions 12R and 12L will be disposed so their axes lie in a vertical plane that is disposed at an angle of 45° with respect to the side and end rails.

The bearing faces 33 of the bracket 30 and the end faces 35 of the side and end rails 18 and 20 are formed for interlocking engagement, and this is accomplished by affording vertical grooves 38 in each of the end faces 35 to receive positioning lugs 40 struck from each of the bearing faces 33. When the upper end portions of the leg sections 12R and 12L have been put in place in the end clamps 32, the bracket 30 is put in position with its upper edge against the lower face of the top 14 and with the lugs 40 extended into the grooves 38, and the assembly is secured in this position by drawing the center portion 31 of the bracket in an inward direction. For this purpose the bracket 30 has a clamping bolt 42 secured as by welding at 43 in a central location on the portion 31 so as to extend inwardly at right angles to the plane in which the leg portions 12R and 12L are to be disposed.

When the bracket 30 is thus disposed in position on the table, the bolt 42 is extended through an opening 44 in an anchoring bar 45, and a clamping nut 46 is threaded onto the inner end of the bolt 42. The opposite ends of the anchoring bar 45 are seated in locating notches 48 formed respectively in the inner faces of the adjacent side and end rails 18 and 20 so as to locate the bar 45 at an angle of 45° with respect to the side and end rails 18 and 20, and hence, by tightening the nut 46, the center portion 31 of the corner bracket may be drawn inwardly so as to tightly clamp the bracket 30 against the ends of the side and end rails while at the same time effecting a tight clamping of the leg portions 12R and 12L within the end clamps 32.

The clamping of the leg portions 12R and 12L within the end clamps 32 in accordance with the present invention is attained by forming the end clamps with opposed side portions adapted to embrace opposite side surfaces of a leg portion, and one of each such pair of side portions is arranged to abut against the end of a side or end rail while the other one of such side portions is arranged to be forced toward the embraced leg portion by the central portion 31 of the corner bracket. Thus the portion 33 of each end clamp is joined in a bendable relation to a portion 33A, which is arcuate in cross section and is joined at 31A to the adjacent edge of the central section 31, and this point of joinder at 31A is so located that tightening of the bolt 42 tends to tighten the portion 33A about the leg portion while at the same time clamping the portion 33 against the end surface 35.

The attachment of the bolt 42 to the corner bracket 30 may be simplified in some instances as shown in Fig. 5. Thus the central portion 31C may have a non-circular opening 49 therein, and the bolt 42A, having a head 50 and a non-circular shank 51, may be extended through the central portion 31C. Thus the bolt 42A accomplishes the functions hereinabove described for the bolt 42, and while the welded joint 43 is eliminated.

From the foregoing description it will be apparent that the present invention provides a novel and highly attractive table construction

wherein the metallic corner brackets not only afford a connection between adjacent side and end rails of the table while at the same time serving to secure the table legs in position.

Thus, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims:

I claim:

1. In a table or like structure having a top member with depending side and end rails fixed thereto adjacent to the side and end edges of the top member, the side and end rails terminating in spaced relation in end edges having vertically extending slots therein, corner brackets for joining the adjacent ends of said side and end rails, each of said corner brackets being formed from sheet metal to afford a central section and a pair of clamp portions each adapted to receive a leg portion, a pair of lugs on each corner bracket

20 adapted to extend into said slots, and means including an anchoring bar for each bracket and operable to hold said brackets in clamping relation to said leg portions and in operative connecting relation to the adjacent side and end rails.

2. In a table or like structure having a top member with depending side and end rails fixed thereto adjacent to the sides and ends of the top member, the side and end rails terminating in spaced relation in end edges having vertically extending slots therein, corner brackets for joining the adjacent ends of said side and end rails, each of said corner brackets being formed from sheet metal to afford a central section and a pair of clamp portions each adapted to receive a leg portion, a pair of lugs on each corner bracket adapted to extend into said slots, and means including a clamping bolt and an anchoring bar for each bracket and operable to hold said brackets in clamping relation to said leg portions and in operative connecting relation to the adjacent side and end rails.

3. In a table or like structure having a top member with depending side and end rails fixed thereto adjacent to the side and end edges of the top member, the side and end rails terminating in spaced relation in end edges having vertically extending slots therein, corner brackets for joining the adjacent ends of said side and end rails, each of said corner brackets being formed from sheet metal to afford a central section and a pair of clamp portions each adapted to receive a leg portion, a pair of lugs on each corner bracket adapted to extend into said slots, and means for each bracket for imparting an inward force to the central section thereof to hold said brackets in clamping relation to said leg portions and in operative connecting relation to the adjacent side and end rails.

4. In a table or like structure having a top member with depending side and end rails fixed thereto adjacent to the side and end edges of the top member, the side and end rails terminating in spaced relation in end edges having vertically extending slots therein, corner brackets for joining the adjacent ends of said side and end rails, each of said corner brackets being formed from sheet metal to afford a central section and a pair of clamp portions each adapted to receive a leg portion, a pair of lugs on each corner bracket

adapted to extend into said slots, a bolt connected to said central portion of each bracket and extending inwardly therefrom, an anchoring bar extended between the adjacent end portions of the side and end rails at each corner of the table, and means associating the bolt at each corner with the anchoring bar at such corner to hold said brackets in clamping relation to said leg portions and in operative connecting relation to the adjacent side and end rails.
